United States Patent Office.

LORENZO MATT, OF BOSTON, MASSACHUSETTS.

Letters Patent No. 72,745, dated December 31, 1867.

IMPROVEMENT IN SOUND-BOARDS FOR PIANO-FORTES.

The Schedule referred to in these Letters Patent and making part of the same.

TO ALL PERSONS TO WHOM THESE PRESENTS SHALL COME:

Be it known that I, LORENZO MATT, of Boston, in the county of Suffolk, and State of Massachusetts, have invented a new and useful Improvement in Sounding-Boards for Piano-Fortes; and I do hereby declare the same to be fully described in the following specification, and represented in the accompanying drawings, of which—

Figure 1 is an under side view; and

Figure 2 a transverse section of a sounding-board constructed in accordance with my invention.

The nature or principle on which, therefore, my improvement is based, consists in constructing the sounding-board of a series of thin boards or strata, laid one upon another, and glued together, and having their grain running lengthwise of each, and so that that of each one of them shall cross that of the next adjacent one at acute angles, the same being to prevent the sounding-board, when completed, from being cracked lengthwise by variations of temperature or hygrometric changes.

In carrying out my invention or improvement, each of the sections or boards I usually make triangular in its transverse section, each being of a width less than that immediately next to and over it, and tapered in its transverse section, and I arrange them together in manner as exhibited in the drawings, in which *a b c* are three boards composing the sounding-board, each of such boards being wider at one than its opposite end, the directions of the grain of each being also shown by lines in the drawings.

Another common method of making a sounding-board for a piano is to form it of one or more boards, glued together at their edges, and braced by a series of wooden bars crossing one another, and glued or fastened to the bottom surface of the board. By this form of construction, the board has an even thickness throughout, and consequently will not vibrate so well as when made tapering transversely.

I find that a sounding-board constructed in my improved manner will vibrate to better advantage, and give a better tone to each string of the instrument, than a board will when made of boards glued together at their edges and braced on their lower surfaces.

I do not claim a sounding-board made of several layers of wood glued together, and having the grain of each crossing that of the layer next to it, or otherwise made as represented in the United States Patent, No. 8,575, but

I claim as my invention, the improved sounding-board made substantially as described, viz, of a series of layers of wood, differing in their widths, and tapering in their transverse sections, and laid flatwise on each other, and glued or cemented together with the grain of each one of the series crossing that of the next adjacent one at acute angles, all essentially as hereinbefore described, and as represented in the accompanying drawings.

LORENZO MATT.
